Application November 5, 1949, Serial No. 125,786

16 Claims. (Cl. 125—30)

1

This invention relates to machines for the manufacture of wire drawing dies, and more particularly to a universal machine which may be used to countersink, drill, shape, recut, and polish a hard die material to a finished wire drawing die. These operations are performed by alapping process in which an abrasive material, commonly diamond powder suspended in oil or other liquid, is applied to a rapidly rotating needle-like drill, usually steel. The support carrying the die or die material and the rotating holder for the needle are axially reciprocated relative to each other so as to bring the needle, charged with abrasive, into contact with the diamond to effect the desired cutting or polishing thereof. The hard die material will sometimes be referred to herein merely as "diamond," but it is to be understood that the machine of the present invention will be useful as well in the manufacture of wire drawing dies made from tungsten carbide or other hard materials. As used herein, the term "drilling" is not restricted to the step of piercing the diamond, but is used generically to include the various cutting and polishing steps in the manufacture of a wire drawing die which are performed by the lapping process.

It is an object of the invention to provide improved apparatus for the manufacture of wire drawing dies. It also is an object of the invention to provide universal apparatus which may be used to perform efficiently all of the steps involved in piercing and finishing a wire drawing die. It is a further object of the invention to provide a multiple unit apparatus in which a plurality of wire drawing dies in various stages of the manufacturing process can be simultaneously worked on, each with maximum efficiency, by a relatively inexperienced operator. Other objects and advantages of the invention will appear hereinafter.

A preferred embodiment of the invention has been selected for purposes of illustration and description and is shown in the accompanying drawings wherein:

Figure 1 is a top plan view of a sixteen spindle machine, three of the drilling units being substantially fully shown and the other thirteen being partially shown;

Figure 2 is a side elevation of the machine with only one of the drilling units being shown, and with part of the apparatus broken away in vertical section to disclose the construction more clearly;

Figure 3 is a front elevation of the machine, looking toward the left side of Figure 2, only

2

one of the drilling units being shown, and part of the construction being broken away in vertical section;

Figure 4 is a horizontal section through the machine substantially on line 4—4 of Figure 2, disclosing the belt drives for rotating the die supports;

Figure 5 is a vertical section through the die plate or work-supporting spindle and cam, substantially on line 5—5 of Figure 3; and

Figure 6 is a vertical section through the roller spindle mounting, substantially on line 6—6 of Figure 3.

In the manufacture of diamond wire drawing dies, the cutting member commonly comprises a sharpened steel needle secured to the lower end of a spindle rotating at speeds which usually lie in the range of about 2500 to 4500 R. P. M. The diamond, which may be encased in metal except for relatively small exposed areas at the ends of the die opening which is to be drilled, is mounted on a holder which has a short reciprocatory motion along the axis of the spindle supporting the drilling needle, and which also may be rotated, at relatively lower speed, in the opposite direction to the needle. Diamond powder of suitable grade or size, which varies depending on the particular operation being performed on the diamond, is mixed with a liquid and applied to the rotating needle to cut and polish the diamond by a lapping operation.

In commercial machines of the prior art there usually are a plurality of vertical needle spindles, and the speed of all spindles is the same, even though there may be a wide variation in the size of the holes being drilled and in the stage of progress of the drilling, shaping or finishing operations for the several die blanks being processed in the machine at any one time. Control of the drilling operation for any particular die blank in such machines is possible only through the shape of the drilling needle, and through the grade or size of diamond powder or other abrasive used. Much depends on the experience and judgment of the machine operator to produce an acceptable finished die, and serious limitations are imposed even on the experienced operator.

According to the present invention, improved apparatus is provided for the manufacture of wire drawing dies in which the operator of a multiple spindle machine may individually adjust the speed of each spindle of the machine to that most suitable for the operation being performed by that particular needle on its particular die. Moreover, the speed and extent of reciprocation

of the die holder relative to the needle spindle may be selected individually, and the pressure of the needle on the diamond, and the time of contact therebetween, may be individually adjusted for most efficient performance.

Less skill and experience is required of the operator to produce satisfactory dies, and it is possible to produce dies of more uniformly high quality in less time and at lower cost. Moreover, by reason of its construction, the machine of the present invention permits a single operator to handle simultaneously and efficiently a larger number of spindles than is possible with wire die machines heretofore known, and with less fatigue and strain.

Referring now more particularly to the drawings, wherein like reference characters denote similar parts, and first to Figures 2 and 3, the machine of the illustrative embodiment comprises a stationary turntable base 11, which is mounted on the top 12 of a table or similar support. The turntable base comprises a circular ring, which may be made of cast iron. The lower edge of this ring has an outwardly flared flange 14 which rests on the table top 12 and is secured thereto by screws or bolts 13.

Spanning the interior of the ring 11, and secured thereto by screws, is a bar, spider or plate 16, preferably made of steel, which serves to support the main drive shaft 17, as will appear more particularly hereinafter. The upper edge of the ring 11 is provided with a circular raceway 15.

Mounted on the turntable base 11, and free to rotate about its longitudinal axis, is a vertically disposed cylindrical housing consisting of aligned lower and upper cylindrical members 18 and 19, respectively, which conveniently are made of cast iron. As far as the operation of the machine is concerned, the members 18 and 19 may be made as one, but for convenience in manufacture, the cylindrical housing preferably is made in two parts which are joined together by screws or bolts 20 passing through interior flanges or matching lugs, as shown.

The lower edge 26 of the cylindrical member 18 is machined to fit the circular raceway 15 and is free to turn therein, thus permitting the cylindrical housing 18-19 to be rotated about its longitudinal axis on the turntable base. Suitable bearing surfaces will be provided, or ball or roller bearings may be employed, if desired, to insure ease of rotation.

Means may be provided for selectively holding the cylindrical housing 18-19 against rotation, relative to the turntable base 11, in a plurality of different positions. As shown, the lower edge 26 of the cylindrical member 18 is provided around its periphery with a plurality of equally spaced holes 34, which are adapted to be engaged by the inner end of the plunger 35. Surrounding the plunger, between collar 37 and guide 36, is a compression coil spring 38, which normally presses the plunger inwardly. The outer end of the plunger 35 may be provided with a knob 39 or the like for the convenience of the machine operator. Withdrawing the inner end of the plunger from the hole 34 in which it happens to be engaged permits the cylindrical member 18-19 to be turned in either direction about its longitudinal axis, until the plunger is released to engage another one of the holes 34. The number and positioning of the holes 34 in the edge 26 is such that the cylindrical member 18-19 can be held against rotation with any one of the drilling spindle units, to be described, directly in front of the operator.

The lower cylindrical member 18 is provided with a plurality of circumferentially spaced openings 21 around its periphery to permit the passage of belts which serve to drive the work-supporting spindles from the main drive shaft 17, in the manner which will be described hereinafter.

The upper part of the cylindrical housing 18-19 is formed so that there can easily be mounted thereon, or secured thereto, spaced circumferentially therearound, a plurality of drilling spindle units, each unit comprising a drill-carrying spindle and an aligned work-supporting spindle. In the illustrative embodiment, the drill-carrying spindle and the work-supporting spindle of each unit are mounted in a bracket 22, which is secured to the outer surface of the cylindrical member 19, but it will be understood that considerable variation in the mounting of the spindles on the cylindrical member 18-19 is possible within the scope of the subjoined claims.

In the illustrative embodiment there are sixteen of these drilling spindle units, but it will be understood that the number may vary. Preferably the number of drilling spindle units will be such that the operator of the completed machine will just be nicely able to take care of all of the drilling spindles in the normal course of wire drawing die manufacturing operations.

As shown, the lower and upper ends of the cylindrical member 19 are formed with thickened rims, each of which is provided exteriorly with a plurality of flat surfaces which give to the rim a polygonal contour. The flat surfaces 23 on the lower rim are aligned with the flat surfaces 24 on the upper rim, so that the drilling spindle brackets 22 of the illustrative embodiment can be readily secured to the cylindrical member 19, as will appear hereinafter.

Extending across the top of the cylindrical member 19 and secured thereto, as by screws, is a cross arm 25, which, as will be explained, supports a bearing for the upper end of the main drive shaft 17. This cross arm may be made of cast iron.

The arrangement of the sixteen drilling spindle units 22 around the periphery of the cylindrical member 19 can be seen in Figure 1, which is a top plan view of the machine. In this view, three of the drilling spindle brackets with their associated equipment are fully shown. It will be understood that the other thirteen drilling spindle brackets will be similar in all important respects and that they are incompletely shown here merely to simplify the drawings.

In Figures 2 and 3, a single drilling spindle bracket is shown secured on the cylindrical member 19, but again this is merely for the purpose of simplifying and clarifying the drawings, and it will be understood that the completed machine will have sixteen of the drilling spindle brackets uniformly spaced around the cylindrical member 19. The construction of the drilling spindle brackets of the illustrative embodiment, and their method of attachment to the cylindrical member 19, may be understood by reference to Figures 1, 2 and 3.

The drilling spindle brackets 22 ordinarily will be made from cast iron. The brackets may all be alike, although only part of them need have spindles projecting downwardly therefrom for mounting idler sheaves, as will appear more fully hereinafter.

The vertical or back plate 28 of the bracket 22 is rectangular in shape, substantially coextensive in length with the cylindrical member

19, and of a width equal to or slightly less than the horizontal dimension of the flat surfaces 23, 24. Holes are drilled through the back plate 28 near its upper and lower ends to receive screws 27 which engage tapped holes in the flat surfaces 23 and 24. These screws 27 secure the bracket 22 firmly on the cylindrical member 19.

Projecting outwardly from the lower portion of the back plate 28 is the sole 29. In the outer end of sole 29 is mounted the die plate, or work-supporting, spindle 32. Projecting outwardly from the upper portion of the back plate 28 is the sole 30, in the outer end of which is mounted the drill-carrying spindle 33, which is aligned with the work-supporting spindle 32. The soles 29 and 30 desirably are reinforced by a web such as is shown at 31, extending outwardly from the back plate 28.

The soles 29 and 30 are of substantially similar shape and dimensions. As can be seen from Figures 1 and 3, the center lines of these soles do not extend radially from the cylindrical member 19, but instead are curved so that the aligned spindles 32 and 33 are displaced to one side, to the left as viewed in Figure 2, of a vertical plane 25 passing through the longitudinal axis of the cylindrical member 19 and also through the vertical center line of the back plate 28. As will appear more fully hereinafter, this displacement facilitates connecting the drill-carrying spindle 30 to the variable speed transmission by a means of a flexible shaft, without enlarging the machine to a point which would make it impractical.

A method of mounting the work-supporting spindle 32 in the outer end of the sole 29 is shown in detail in Figure 5. The thickened end of the sole has a vertical bore to receive the flanged sleeve 41. This sleeve may be secured in the bore of the sole in known conventional manner, for example by means of screws which extend downwardly through drilled openings in the flange and engage tapped holes in the sole, as shown. Rotatably and slidably mounted within the sleeve 41, with ball or other suitable bearings, is the spindle 32.

Secured on the upper end of the spindle 32 is the die plate or work support 42. A plurality of concentric grooves may be cut in the upper surface of the work support, as shown, or it may be otherwise treated to facilitate sticking a diamond die thereon in known manner. Surrounding the spindle 32 and located between its upper bearing and the work support 42 is a compression coil spring 43, which normally presses the work support and attached spindle upwardly. Preferably the coil spring 43 is enclosed, for example by providing the upper end of the sleeve 41 and the lower edge of the work support 42 with telescoping sleeves, as shown.

Secured on the lower end of the spindle 32, as by means of a set screw, is the cam-faced sheave 45. The upper surface of the sheave rim, which is the cam face, engages the lower, or bearing, end of the cam activating screw 46. The other end of the cam activating screw is threaded into the tapped hole 47 in the sole 29, where it is held in desired adjusted position by the lock nut 48. By adjusting the cam activating screw 46 up or down in the hole 47, it is possible to raise or lower the work support 42 relative to the drill-carrying spindle 33.

When the spindle 32 is rotated, the cam face on the sheave 45 moves under the stationary bearing end of the cam activating screw 46, and either maintains the spindle at a constant height,

or forces the spindle downwardly against the pressure of the spring 43, or permits the spindle to rise under the effect of the spring pressure, depending on the nature of the cam surface which is passing under the cam activating screw at any particular instant.

Ordinarily, the cams will be alike on all of the work-supporting spindles and a preferred embodiment is illustrated. However, considerable variation in the amount and frequency of the vertical movement of the work support is possible simply by substituting one cam-faced sheave for another. If special circumstances require it, a cam-faced sheave providing vertical movement of any work support peculiarly suited to the operation being performed on the die which is mounted on that particular work support may be selected.

Using a double cam-faced sheave such as is shown in the illustrative embodiment, the work support will successively rise, dwell, fall, dwell, rise, dwell, fall, and dwell in one turn of the spindle, and this series of steps will be repeated as the spindle continues to turn. The rise and fall intervals may each continue, for example, through 60° of rotation, and the dwell intervals may be 30° each.

By watching the wear of any drilling needle as it is exposed during the lower dwell periods, the operator can regulate the vertical adjustment of that needle, in manner hereinafter described, to secure maximum cutting and efficiency. When the needle shows excessive wear, it should be lowered sufficiently to maintain efficient cutting. This individual adjustability of the needles makes possible and facilitates the efficient performance of different operations simultaneously on a plurality of diamond dies by a single machine.

In an alternative form of cam, the work piece will rise and fall once, instead of twice, for each turn of the spindle, and it will be understood that other variations are possible. Also, the amount of the cam rise may vary on different cam sheaves. In a cam of the preferred type shown in the drawings, a cam rise of three-sixteenths inch is easily permissible with a cam sheave diameter of three inches, and this provides efficient operation.

The work-supporting spindle 32 will be rotated by a flexible band which engages the grooved rim of the cam-faced sheave 45. It will be desirable to provide a common driving band for a plurality of these sheaves on a machine. When the machine is in operation, the sheaves all will be moving up and down, within their short limited ranges, and since the cam surfaces for the several spindles may vary considerably, it would be impractical, if not impossible, to synchronize such movements. Consequently, a round belt or cord will be employed as the driving band and the grooves in the sheaves will be cut deep enough to minimize any danger of the belt being thrown off unintentionally.

A considerable variation in the layout of the belt driving connections for the work-supporting spindles of the machine of the present invention is possible. A preferred layout for a sixteen drilling spindle machine such as is herein described is disclosed in Figure 4 of the application drawings, wherein the spindles are driven as groups of four.

A belt 51 extends around four of the cam-faced sheaves 45, and around a step-down idler sheave 52. Conveniently the belt will be tensioned by

pressure exerted by the idler sheave 53. As may be seen in Figures 2 and 3, the step-down idler sheave 52 comprises three axially aligned sheaves, all secured together so as to turn as one, one of the sheaves being larger than the other two. One of the two smaller sheaves serves to drive the belt 51, and the other drives a similar belt 54 passing around another group of four cam-faced sheaves 45.

The larger sheave of the stepdown idler 52 is rotatably secured on the lower end of a spindle 55, and the upper end of this spindle is secured, as by means of a set screw, in the boss 56 depending from the lower side of the sole 29. The belt tensioning idler sheave 53 may be rotatably mounted at one end of a short crank or lever, the other end of which is pivoted on a spindle secured in the boss 56 of an adjacent drilling spindle bracket. The desired tension in the belt may be attained by adjustment and setting of the crank on the spindle, or continuously by spring pressure, in known manner.

The step-down idler sheave 52 is driven from the main drive shaft 17 by means of a flexible band 58 passing around the larger sheave, through one of the openings 21 in the wall of the cylindrical member 18, and around a pulley 59 secured on the shaft 17. A V belt is suitable for this driving connection. Rotation of the main drive shaft 17 will cause the belt 58 to turn the step-down idler sheave 52 which, in turn, will cause the belts 51 and 54 each to rotate four of the cam-faced sheaves 45 and their associated work-supporting spindles 32.

Another pulley 59' on the main drive shaft will cause the belt 58' to turn another step-down idler sheave 52', similar to 52, and in turn cause the belts 51' and 54' each to drive four cam-faced sheaves 45 with their work-supporting spindles.

Thus, all of the work-supporting spindles will be rotated upon rotation of the main drive shaft. With the particular driving layout illustrated, the work-supporting spindles all will be driven in the same direction and at the same speed. Some variation in the speed of the work-supporting spindles, in groups of four, is possible by the substitution of different step-down idler sheaves. The belts 58 and 58' passing through openings 21 in the cylindrical member 18 do not, of course, interfere in any way with turning the cylindrical housing 18-19 on the turntable base 11 to bring any particular drilling spindle unit into position directly in front of the operator.

The main drive shaft 17 will be driven through suitable connection at its lower end to a motor or other source of power, not shown. Desirably, the weight of the shaft is borne by the bearing 60, supported by the bar 16 spanning the interior of the turntable base 11.

The high speed drill-carrying spindle 33, which is aligned with the work-supporting spindle 32, is mounted in the outer end of the upper sole 30 of the drilling spindle bracket, conveniently in a manner generally similar to that employed for mounting the work-supporting spindle. The construction will be understood from Figures 1, 2 and 3 of the application drawings, to which reference is now made.

The thickened outer end of the sole 30 has a vertical bore to receive a flanged sleeve 62. This sleeve 62, which projects both above and below the sole, may be secured in the sole in the same manner that the flanged sleeve 61 is secured in the lower sole 29.

The upper end of the flanged sleeve 62 is split longitudinally on one side for a short distance, and is cut transversely for a distance equal to approximately one-sixth of the circumference on each side of the longitudinal split, at the lower end thereof, to provide two ears which can be flexed slightly to exert a clamping action. A hand screw 63 is associated with the two ears in known manner for adjusting the clamping effect.

10 Within the bore of the sleeve 62 is a split bushing adapter 64, which desirably will be flanged at its upper end to prevent dropping through the sleeve. Slidably mounted within the split bushing adapter 64 is a cylindrical housing 61 containing ball or other suitable high speed bearings for the drill spindle 33. When the hand screw 63 is tightened, the spindle housing 61 will be held firmly by the split bushing adapter against vertical movement. By loosening the hand screw it is 15 possible to move the spindle housing 61 up or down, and thus adjust the needle drill relative to the work support 42. Secured to the lower end of the spindle 33 is a chuck or other suitable means 65 for attaching a needle drill to the end 20 of the spindle.

Connected to the upper end of the spindle housing 61 by suitable coupling means is one end of the flexible shaft 66. The rotatable core portion of this flexible shaft is connected to the drill-carrying spindle 33, so that rotation of the shaft will turn the spindle. The other end of the flexible shaft 66 is connected to the outer end of the cylindrical housing 68, which is disposed and adjustable radially of the machine. The housing 68 contains high speed bearings for the roller spindle 69, to which the rotatable core portion of the shaft is connected. The housing 68 may be similar to the housing 61.

40 The flexible shaft 66, connected at one end to a spindle housing adjustable in a horizontal plane and at the other end to a vertically adjustable spindle housing, should be trained so that adjustment of the spindle housings will not produce sharp localized bending of the shaft such as might interfere with its efficient operation. 45 This result could be accomplished simply by separating the two spindles sufficiently, but it is desirable, of course, to keep the overall dimensions of the machine small. In the machine of the present invention, the axes of the two spindles do not lie in a common plane and therefore the spindles may be mounted very close to each other and connected by the flexible shaft arranged in the form of a loop, as shown in the drawing. Adjustment of the spindle housings merely increases or decreases the size of the loop slightly, which does not interfere with the efficient operation of the shaft. At the same time, the machine is kept small in size.

50 As may be seen in Figure 6, the roller spindle housing 68 is slidably mounted in the transverse sleeve portion 70 at the upper end of the tubular support 71. One end of this sleeve portion is provided with clamping ears and an adjusting hand screw 72 similar to those on the upper end of the flanged sleeve 62. When the roller spindle housing is adjusted to the desired position within the sleeve 20, the hand screw 72 may be tightened to clamp the housing 68 firmly in the sleeve.

55 As can be seen in Figure 6, the tubular lower portion of the support 71 is slidably mounted in a boss 73 formed integral with and extending upwardly from the upper surface of the sole 30. The support 71 is resiliently held down in the boss 73, for example by a tension coil spring 74 lying with-

in the tubular support and secured at its upper end to the support and at its lower end to the sole 30.

Extending for a short distance downwardly from the sleeve 70, the tubular support 71 is slotted transversely as shown at 78 to permit passage of the rod 75 therethrough without interfering with limited vertical movement of the support. One end of this rod 75 is rotatable in holes through the upper end of the boss 73 and the other end is provided with a knob or handle 76 so that the operator of the machine can turn the rod readily.

Secured to the rod 75 are two similar cams 77, one on each side of the boss 73. The edges of these cams bear against the under side of the sleeve 70. As the rod 75 is turned, the cams 77 move the sleeve 70 and connected support 71 upwardly against the tension of the coil spring 74, or permit the spring to draw the support down into the boss. The purpose of this adjustment is to make and break the driving connection to the roller spindle 69 and the flexible shaft, as will appear hereinafter.

Secured on the free end of the roller spindle 69, that is the end opposite the coupling to the flexible shaft, is a roller 80. The edge of this roller preferably is rounded and is made of rubber or other material having a relatively high coefficient of friction.

When the rod 75 is turned so that the support 71 is pulled down into the boss 73 by the spring 74, the edge of the roller 80 will be pressed resiliently against the top surface of the horizontally disposed spindle driving disc 81. This driving disc preferably is made of phenolic laminated material such as is sold under the name Texolite, or similar non-metallic material, and is attached to the hub 82 which is secured on the upper end of the main drive shaft 17.

When the main drive shaft 17 is rotated and the roller 80 is in contact with the spindle driving disc 81, the connection through the flexible shaft 66 will cause the drill-carrying spindle 33 to be rotated. This driving connection may be broken at the will of the operator merely by turning the rod 75 a half turn so that the cams 77 will lift the roller spindle support and thus lift the roller 80 out of contact with the spindle driving disc 81. The speed of the drill-carrying spindle may be varied over a considerable range by loosening the hand screw 72 and moving the roller spindle housing 68 in or out, depending on whether it is desired to decrease or increase the spindle speed.

It will be obvious that the controls for each drill-carrying spindle of the diamond die making machine may be adjusted to the conditions best suited for the operation being performed by that particular drilling spindle unit. The speed of each drill-carrying spindle may be varied without regard to the speeds in the other drilling units of the machine, and the driving connection to any particular drill-carrying spindle may be broken at the will of the operator without interfering in any way with the operation of the remaining drilling units.

The pressure of the drilling needle on the diamond die may be varied by adjusting the height of the drill-carrying spindle. This pressure also may be varied by adjustment of the cam-activating screw which bears against the cam-faced sheave on the lower end of the work-supporting spindle. The reciprocating vertical movement of the work-supporting spindle may be varied by

substitution of one cam-faced sheave for another on the lower end of the spindle.

It will be evident from the foregoing description that the operator will have complete control over all of the variable factors in the operation of the machine which affect the manufacture of a wire drawing die. That being the case, the procedure can be substantially standardized, providing for a given period of drilling under certain specified conditions, to be followed by another period of drilling under certain other specified conditions, and so on. Automatic timing mechanism may be employed in this connection. With the machine of the present invention it thus becomes possible for relatively inexperienced operators to produce wire drawing dies of uniformly high quality expeditiously and efficiently. The objects of the invention are accomplished.

The invention herein disclosed may be variously modified and embodied within the scope of the subjoined claims.

We claim:

1. Apparatus for the manufacture of wire drawing dies wherein an abrasive medium is applied to the point of a rotating needle-like drill, comprising, in combination, a turntable base, a vertically disposed cylindrical housing mounted for rotation about its longitudinal axis on said turntable base, means for holding said housing against rotation relative to the base at a plurality of positions of relative rotation, a plurality of spindle-supporting brackets secured to the exterior of said housing and spaced around its periphery, a vertical drill-carrying spindle mounted in each bracket, a vertical work-holding spindle mounted in each bracket below and in alignment with the drill-carrying spindle, a vertical drive shaft co-axially located within said housing, means for driving the drill-carrying spindles from said drive shaft regardless of the relative rotary position of the housing on the turntable base, the means for driving the drill-carrying spindles including means adjustable while the apparatus is in operation for individually varying the speeds of the drill-carrying spindles, means for driving the work-holding spindles from said drive shaft regardless of the relative rotary position of the housing on the turntable base, and cam devices individual to said work-holding spindles for reciprocating the work-holding spindles through short ranges along their longitudinal axes automatically as they rotate.

2. Apparatus for the manufacture of wire drawing dies wherein an abrasive medium is applied to the point of a rotating needle-like drill, comprising, in combination, a turntable base, a vertically disposed cylindrical housing mounted for rotation about its longitudinal axis on said turntable base, means for holding said housing against rotation relative to the base at a plurality of positions of relative rotation, a plurality of drilling spindle units secured to the said housing and spaced around its periphery, each drilling spindle unit comprising a vertical drill-carrying spindle and a vertical work-holding spindle mounted below and in alignment with the drill-carrying spindle, a vertical drive shaft co-axially located within said housing, means for driving the drill-carrying spindles from said drive shaft regardless of the relative rotary position of the housing on the turntable base, the means for driving the drill-carrying spindles including means adjustable while the apparatus

is in operation for individually varying the speeds of the drill-carrying spindles, and means for driving the work-holding spindles from said drive shaft regardless of the relative rotary position of the housing on the turntable base.

3. Apparatus for the manufacture of wire drawing dies wherein an abrasive medium is applied to the point of a rotating needle-like drill, comprising, in combination, a turntable base, a vertically disposed cylindrical housing mounted for rotation about its longitudinal axis on said turntable base, means for holding said housing against rotation relative to the base at a plurality of positions of relative rotation, a plurality of drilling spindle units secured to the said housing and spaced around its periphery, each drilling spindle unit comprising a vertical drill-carrying spindle and a vertical work-holding spindle mounted below and in alignment with the drill-carrying spindle, a vertical drive shaft co-axially located within said housing, means for driving the drill-carrying spindles from said drive shaft regardless of the relative rotary position of the housing on the turntable base, means for driving the work-holding spindles from said drive shaft regardless of the relative rotary position of the housing on the turntable base, and cam devices individual to said work-holding spindles for reciprocating the work-holding spindles through short ranges along their longitudinal axes automatically as they rotate.

4. Apparatus for the manufacture of wire drawing dies according to claim 3, including, in combination, means adjustable while the apparatus is in operation for individually varying the speeds of the drill-carrying spindles over a wide range.

5. Apparatus for the manufacture of wire drawing dies according to claim 3, including, in combination, a friction disk and multiple roller transmission between the drive shaft and the drill-carrying spindles.

6. Apparatus for the manufacture of wire drawing dies according to claim 3, including, a combination, a friction-faced disk secured on the upper end of the vertical drive shaft, a plurality of driven rollers operatively associated with the said disk, one roller for each drill-carrying spindle, and driving connections between the said rollers and the drill-carrying spindles.

7. Apparatus for the manufacture of wire drawing dies according to claim 3, including in combination, a friction-faced disk secured on the upper end of the vertical drive shaft, a plurality of driven rollers operatively associated with the said disk, one roller for each drill-carrying spindle, and a flexible shaft connecting each roller to the corresponding drill-carrying spindle.

8. Apparatus for the manufacture of wire drawing dies according to claim 3, including, in combination, a friction-faced disk secured on the upper end of the vertical drive shaft, a plurality of driven rollers operatively associated with the said disk, one roller for each drill-carrying spindle, a spindle for each roller, said roller spindles being disposed radially of the friction-faced disk with the outer end of each roller spindle adjacent the upper end of a drill-carrying spindle, and a flexible shaft connecting each roller spindle to the corresponding drill-carrying spindle, the said flexible shaft forming a loop.

9. Apparatus for the manufacture of wire drawing dies according to claim 3, including, in combination, a friction-faced disk secured on the upper end of the vertical drive shaft, a plu-

rality of driven rollers operatively associated with the said disk, one roller for each drill-carrying spindle, driving connections between the said rollers and the drill-carrying spindles, and means adjustable while the apparatus is in operation for individually interrupting and remaking the driving connections between the disk and the drill-carrying spindles.

10. Apparatus for the manufacture of wire drawing dies according to claim 3, including, in combination, a friction-faced disk secured on the upper end of the vertical drive shaft, a plurality of driven rollers operatively associated with the said disk, one roller for each drill-carrying spindle, means normally exerting a resilient pressure between the rollers and the friction face of the disk, means adjustable while the apparatus is in operation for individually lifting the rollers from the disk and for returning the rollers to engagement with the disk, and driving connections between the said rollers and the drill-carrying spindles.

11. Apparatus for the manufacture of wire drawing dies according to claim 3, including, in combination, a plurality of sheaves secured on the drive shaft, a plurality of countershafts mounted exteriorly of the cylindrical housing, each countershaft having a sheave secured thereon and being connected by a belt extending through an opening in the cylindrical housing to one of the sheaves on the drive shaft, a sheave secured on each work-holding spindle, additional sheaves secured on the countershafts, and belts connecting the latter sheaves to the sheaves on the work-holding spindles for driving the work-holding spindles.

12. Apparatus for the manufacture of wire drawing dies wherein an abrasive medium is applied to the point of a rotating needle-like drill, comprising, in combination, a supporting member, a vertical drill-carrying spindle mounted in the supporting member, a vertical work-holding spindle mounted in the supporting member below and continuously in axial alignment with the drill-carrying spindle, a drive shaft, driving connections between the drive shaft and each of the spindles for simultaneously rotating the two spindles in opposite directions, and a variable speed transmission in the driving connection between the drive shaft and one of the spindles, the said variable speed transmission including means adjustable while the apparatus is in operation to adjust the speed of the spindle to any speed between maximum and minimum without interrupting its rotation.

13. Apparatus for the manufacture of wire drawing dies according to claim 12, in which the variable speed transmission comprises a friction disk and roller with means for adjusting the roller radially over the disk surface.

14. Apparatus for the manufacture of wire drawing dies according to claim 12, in which the variable speed transmission comprises a friction disk and roller with means for adjusting the roller radially over the disk surface, and in which a flexible shaft connects the roller to the spindle.

15. Apparatus for the manufacture of wire drawing dies according to claim 12, including, in combination, means for imparting reciprocatory motion to the constant speed spindle along its longitudinal axis automatically upon rotation of the spindle.

16. Apparatus for the manufacture of wire drawing dies wherein an abrasive medium is ap-

plied to the point of a needle-like drill, comprising, in combination, a supporting member, a vertically disposed spindle mounted in the supporting member and adapted to carry a work piece on the upper end thereof, the mounting for the spindle permitting limited reciprocatory motion of the spindle along its longitudinal axis, spring means normally urging the spindle upwardly, a cam-faced sheave secured on the lower end of the spindle with the cam face up, and means fixed on the under side of the supporting member engaging the cam face for imparting a vertical reciprocatory motion to the spindle upon rotation thereof.
